UNITED STATES PATENT OFFICE.

CHARLES S. BARNARD, OF BRIDGEPORT, CONNECTICUT, ASSIGNEE TO THE BURNS & BASSICK COMPANY, OF BRIDGEPORT, CONNECTICUT, A CORPORATION OF CONNECTICUT.

LUBRICATOR.

1,168,590.

Specification of Letters Patent. Patented Jan. 18, 1916.

Application filed April 9, 1915. Serial No. 20,310.

To all whom it may concern:

Be it known that I, CHARLES S. BARNARD, a citizen of the United States, residing at the city of Bridgeport, county of Fairfield, 5 State of Connecticut, have invented certain new and useful Improvements in Lubricators; and I do declare the following to be a full, clear, and exact description of the invention, such as will enable others skilled 10 in the art to which it appertains to make and use the same.

This invention relates to certain new and useful improvements in lubricators, and the primary object of the invention is to provide 15 a lubricator which has novel means incorporated therein whereby the device may be supplied with oil from or at its top and may be applied in position by means of a screw driver from said top without interference from a movable closure that normally 20 closes the lubricant inlet.

A further object of the invention is to provide improved means for securing the closure in position and for limiting movement 25 of the latter.

In the drawings: Figure 1 is a side elevation; Fig. 2 is a section on the line 2—2 of Fig. 3; Fig. 3 is a top plan view; Fig. 4 is a similar view showing the closure in open 30 position; and Fig. 5 is a section on the line 5—5 of Fig. 1.

The lubricator is composed of a hollow body 1 threaded at its lower end at 2. The body is preferably of cylindrical form and 35 has an integral top 3 in which is formed a screw driver receiving slot 4. Arranged to one side of the slot 4 is an inlet 5 of a size adapted to receive the spout of an oil can whereby oil may be fed into the lubricator 40 body from the top of the latter. The body 1 below the top thereof is formed with an arcuate slot 6 providing shoulders 7 and 8 in which slot is received an arcuate lip 9 formed on the annular skirt or flange 10 of 45 the segmental cover or closure 11. The flange or skirt 10 is knurled or otherwise roughened at 12 so as to provide a finger gripping surface to enable the closure to be easily rotated to open and closed positions. 50 The ends of the lip 9 form stops 13 and 14 which are engageable with the stops 7 and 8 respectively, whereby it will be seen that when the stops 8 and 14 engage, the chord of the segmental top 11 registers with and 55 completely exposes the screw-driver slot 4

as shown in Fig. 3, and when the stops 7 and 13 engage the chord of the segment traverses slot 4 and uncovers the filling inlet 5, as depicted in Fig. 4 of the drawings. Thus the present invention entirely dispenses with the necessity of an inlet in the side of the lubricator body and enables said inlet to be placed in the top of the body, which latter location is obviously more convenient and accessible and is the most natural way of introducing lubricant into the body.

What is claimed is:

1. In a lubricator, a body having a threaded open end and having a top on its opposite end provided with a lubricant inlet, said top having a screw-driver receiving slot to one side of the inlet and said body having an arcuate groove the ends of which form stops, and a cap on the body having a segmental top and a flange which rotates over the body, the free edge of the flange having an arcuate lip which projects into the groove, the ends of said lip forming stops which coact with the first named stops whereby the cap when engaged with one of the first named stops uncovers the inlet and when engaged with the other of the first named stops the chord of the segment alines with said screw-driver receiving slot.

2. In a lubricator, a hollow body having a top with a lubricant inlet therein and having its opposite end threaded, said top having a screw-driver receiving slot therein, and a cap rotatable on the body and having a segmental top the chord of which in one position of the cap alines with said slot and in a second position uncovers the inlet.

3. A lubricator composed of a hollow body having a top with an inlet in the latter and having screw threads on its bottom end, said top having a tool receiving slot therein, and a closure for the top having a segmental top which in one position covers the inlet and in a second position the chord of the closure top registers with the slot.

4. A lubricator composed of a hollow body having a top provided with a slot and an inlet and having screw threads on its bottom end, and a closure for the top having a cutaway part enabling same to completely expose the slot in one position and to cover the inlet in a second position.

5. A lubricator composed of a hollow body having a top provided with a slot

and an inlet and having screw threads on its bottom end, and a closure for the top, said closure being rotatable on the top so as to cover the inlet in one position and to completely expose the slot in a second position.

In testimony whereof I affix my signature in presence of two witnesses.

CHARLES S. BARNARD.
